UNITED STATES PATENT OFFICE.

CHARLES FREEMAN, OF LOS ANGELES, CALIFORNIA.

AUTOMATIC FIREARM.

No. 802,083.

Specification of Letters Patent.

Patented Oct. 17, 1905.

Application filed August 15, 1904. Serial No. 220,740.

To all whom it may concern:

Be it known that I, CHARLES FREEMAN, a citizen of the United States, residing at Los Angeles, in the county of Los Angeles and State of California, have invented a new and useful Automatic Firearm, of which the following is a specification.

This invention embodies a new principle in automatic firearms, which consists in employing a barrel and allowing a device—such, for instance, as the breech-block—a short backward primary movement upon the discharge of the arm, this movement being stopped by suitable locking means. The great bulk of the backward thrust from the explosion in the barrel is solidly opposed by this locking device and the breech-block. Meanwhile a momentum-block, which while the parts are in their closed and locked position is in intimate contact with the breech-block, (which, in fact, it holds in its forward position through pressure exerted by a reaction-spring,) receives an impulse from the short primary movement of the breech-block, the momentum thus imparted to the momentum-block being sufficient to reciprocate it along the frame, unlock the breech-block, pull it backward from the breech, compress a reaction-spring, and operate the arm. The pressure of the reaction-spring then reverses the movement of the momentum-block, which then operates to close the breech and leave the arm in its normal closed position. As carried out by the form of mechanism shown herein the barrel remains stationary. The initial force derived from the discharge of the cartridge gives a slight rearward movement to the breech-block, which movement is checked by a suitable locking device engaging both breech-block and frame. A momentum-block mounted in contact with the breech-block receives the momentum of the breech-block and the momentum of the breech-block is transferred to the momentum-block, so that the latter continues backward after the breech-block is interrupted, and this continued retraction of the momentum-block unlocks the breech-block from the frame and pulls the breech-block back with the momentum-block, thereby opening the breech and removing the empty shell. Part of the energy of the reaction-block has in the meantime been expended in compressing the recoil-spring, which at the termination of the backward movement of the momentum-block reacts, forcing the momentum-block forward to close the breech and to op-

erate the locking device and restore the parts to original position.

Among the advantages of the principle here employed are these: It is possible to use a cartridge of any desired size in a barrel of any length and weight, the barrel being immovable and the backward thrust of the cartridge being solidly opposed by the lock after just sufficient backward movement has been allowed to give momentum to the momentum-block, which operates the parts. The backward movement is very slight, and the more powerful the cartridge employed the shorter will this movement be required. The barrel being immovable, no return-spring is required, therefore no brake to retard its movement and no large abutment to stop its backward and forward movement. As only sufficient of the force of the explosion is employed to operate the parts, the breech is opened and the cartridge ejected without undue force.

The main object of the invention is to carry out the foregoing principle with a simple and effective mechanism; but I do not confine myself to the exact mechanism here employed, but claim all that may justly come within the scope of my invention.

Another object of the invention is to provide a novel trigger mechanism for use in automatic firearms.

Other objects and advantages of the invention will appear in the following description.

The accompanying drawings illustrate the invention, and referring thereto—

Figure 1 is a vertical longitudinal section through the breech of the firearm, illustrating the principle as applied to a rifle. Fig. 2 is a perspective view of the momentum-block, part of its stem being broken away. Fig. 3 is a sectional view taken on line X³ X³, Fig. 1. Fig. 4 is a sectional view taken on line X⁴ X⁴, Fig. 2. Fig. 5 is a perspective view of the breech-block and locking-pin, showing the two parts in the relative positions which they occupy immediately preceding the discharge of the gun. Fig. 6 is a perspective view of the locking-pin. Fig. 7 is a perspective view of the trigger mechanism with the hammer-spring, sear-springs, and trigger-spring removed. Fig. 8 is a plan of the trigger mechanism taken immediately below the hammer. Fig. 9 is a sectional view taken on line X⁹ X⁹, Fig. 1, showing the parts in the position they have before firing. Fig. 10 is a similar view showing the breech-block having been moved back a slight distance by the recoil and brought

into operative contact with the locking-dog. Fig. 11 is a similar view showing the breech-block in a similar position to the preceding and the recoil-block having moved back sufficiently to unlock the locking-dog from engagement with the frame. Fig. 12 is a similar view showing the breech-block, locking-dog, and momentum-block at the extreme rearward position which they have after the discharge.

1 designates the frame, to which the barrel 2 is rigidly attached. The lower front part of the frame 1 is provided with a way 3, while a tube 4 is joined to the frame 1 adjacent the way 3, being incased in a wooden fore-arm 5 below the barrel. The main portion of the frame 1 is chambered to provide a way for the reciprocating movement of the parts therein, and the lower part of the frame 1 is chambered to receive a magazine 6, which may be of the common box-magazine type, as shown.

7 designates in general a momentum-block which comprises a forked member 8, having a stem 9, the forked portion being slidably mounted within the way 3 and the stem 9 lying within the tube 4. A breech-block 10 is slidably mounted upon the momentum-block, the momentum-block being chambered to receive the same and having a plate 11, L-shaped in cross-section. (See Figs. 2 and 4.)

The plate 11 is provided with an angular slot 12, and the momentum-block has an offset portion 13, forming oppositely-disposed abutments 14 and 15. A spring-stop 16 is provided within the tube 4, and the stem 9 has a head 17, while the coil compression-spring 18 is interposed between the head 17 and the stop 16 and serves to normally hold the momentum-block in the position shown in Figs. 1 and 9.

The breech-block 10 is slidably mounted within the plate 11 of the momentum-block, the breech-block being recessed to form shoulders 19 and 20, which are adapted to respectively engage with abutments 15 and 14 to limit the sliding movement in either direction of the breech-block relatively to the momentum-block. The breech-block is provided at one end with a slotted lug 21 and at the other end with a slotted lug 22. A locking-dog 23 is provided with a flat shank 24, which is mounted within the slotted lugs 21 and 22 and which has an elongated slot 25, which receives a pin 26 in the slotted lug 21. A short pin 27 projects up from the shank 24 and lies within the angular slot 12 of the momentum-block.

The shank 24 at its forward end is also provided with a cartridge-extracting hook 28. The breech-block 10 is bored centrally to receive the firing-pin 29, and the locking-dog 23 is provided with a slot 30 to receive the firing-pin. In the operation of the mechanism the locking-dog 23 has a lateral movement relatively to the breech-block, and for

that reason the slot 30 is made elongated, as shown, so that the firing-pin will not impede its lateral movement.

40 designates the hammer, which is pivoted at 41 and operated by the usual spring 42 ⁷⁰ and has a single cocking-notch 43. Pivoted to the frame just below the hammer is an auxiliary sear 44 and a regular sear 45. Both sears are adapted to consecutively engage the cocking-notch 43, the detent of the auxiliary sear 44 being longer from its fulcrum than the detent of the sear 45. (See Figs. 7 and 8.)

The rear end of the auxiliary sear 44 is provided with a toe 46, and while both sears normally lie substantially in the same horizontal plane the toe 46 of the auxiliary sear 44 projects below the plane.

47 designates the trigger, which is provided with an auxiliary pivoted finger 48 and with a rigid regular finger 49. The pivoted auxiliary finger 48 is longer than the finger 49, and when the parts are in the position shown in Fig. 7 the auxiliary finger 48 lies directly under the toe 46 of the auxiliary sear 44, ⁸⁵ while the finger 49 lies under but slightly below the sear 45. An inclined abutment 50 projects from the frame 1 adjacent to the end of the pivoted finger 48. A spring 51 serves to normally hold the pivoted finger 48 under ⁹⁰ the toe 46.

In operation when the hammer has been moved back into the position shown in Figs. 1 and 7 the auxiliary sear 44 engages the cocking-notch 43 and retains the hammer in position. Upon pulling the trigger 47 as the finger 48 rises it presses upon the toe 46 and tilts the sear 44, which releases the hammer which moves slightly forward and is caught by the sear 45 after a slight movement. Continued pulling on the trigger, however, will quickly bring the finger 49 into engagement with the sear 45, so that the latter is tilted and the hammer thereby released, and in the meantime as the finger 48 moves up it is shunted from the toe 46 by the inclined abutment 50, so that the sear 44 will immediately spring back to position, with its detent riding against the rounded hub of the hammer in position to catch the hammer as soon as the cocking-notch again arrives in place, upon the next backward movement of the hammer. As soon as the trigger 47 is released it returns to its normal position, the finger 48 riding down the side of the toe 46, ¹⁰ under which it is snapped by the spring 51 upon the completion of the return movement of the trigger. Thus the hammer is always caught by the auxiliary sear 44 when thrown back.

Referring to Fig. 1, a cartridge is shown in place ready to be discharged and the hammer is cocked.

Fig. 9 shows the breech-block, momentum-block, and locking-dog in the positions they

have corresponding to the view in Fig. 1. In this position the locking-dog is in engagement with a locking-notch 35 in the frame, and the breech-block is shown slightly ahead of the locking-dog, leaving a narrow space 36, the abutment 15 lying close against the shoulder 19, with the cartridge abutting against the end of the breech-block, as shown, the cartridge-extracting hook being out of engagement with the rim of the cartridge. By pulling the trigger the hammer is released, and it strikes the firing-pin, which explodes the cartridge. The recoil drives the breech-block backward, closing the space 36, where it is interrupted by its coming into contact with the locking-dog. The parts now have the position shown in Fig. 10. Up to this time the locking-dog is still in engagement with the frame, and thus the backward movement of the breech-block is positively arrested; but the momentum-block under the impulse derived from the initial recoil of the breech-block continues on backward, and as the angular slot 12 moves along the pin 27 it rocks the locking-dog upon the pin 26 and disengages the locking-dog from the frame, whereupon the breech-block and locking-dog are both bodily moved backward by the momentum-block to the end of its rear stroke. The hook 28 on the locking-dog, which catches over the rim of the cartridge-shell, carries the shell back also with the parts, and during this backward movement the rim of the shell strikes an ejector (not shown) and is ejected in the well-known manner. As soon as the parts reach this position, as shown in Fig. 12, the cartridge is ejected through the side of the frame through the action of a cartridge-stop, (not shown,) and a fresh cartridge from the magazine springs into place. During the rearward movement of the momentum-block the spring 18 is compressed, and at the termination of the rear movement it reacts and drives the momentum-block forward, carrying with it the breech-block and locking-pin and the fresh cartridge. It will be observed that the breech-block and locking-dog do not lag behind this forward movement of the momentum-block, as lost motion is obviated, for the reason that the slot 12 cannot slide along the pin 27, as the pin 27 is held from lateral movement by reason of the locking-dog bearing against the inside face of the frame; but as soon as the locking-dog is sufficiently moved forward until its side comes opposite the locking-notch 35 the front end of the shoulder 32 strikes the frame, which arrests the forward movement of the locking-dog, and the continued forward movement of the momentum-block and breech-block throws the locking-dog into the locking-notch 35 by reason of the inclined slot 12 sliding over the pin 27, and after the locking-dog is seated in the locking-notch the momentum-block and breech-block have a further slight movement forward, which brings the breech-block out of contact with

the shoulder of the locking-dog, thus providing for the slight backward thrust which transmits the recoil energy to the momentum-block, which operates the arm.

What I claim is—

1. In an automatic firearm, a frame, a barrel mounted on said frame, a breech-block mounted in the frame, a momentum-block mounted in the frame, the breech-block having a short primary movement imparted by an explosion in the barrel and a subsequent longer movement derived from the momentum-block, a recoil-spring, and means for stopping the breech-block after the short primary movement, energy derived from the recoil being imparted to the momentum-block to again actuate the breech-block, compress the recoil-spring and operate the arm. 70

2. In an automatic firearm, a frame, a barrel rigidly mounted on said frame, a breech-block mounted in the frame, a momentum-block mounted in the frame, the breech-block having a short primary movement imparted by an explosion in the barrel and a subsequent longer movement derived from the momentum-block, a recoil-spring, and means for stopping the breech-block after the short primary movement, energy derived from the discharge being imparted through the short primary movement of the breech-block to the momentum-block to release the breech-block and again actuate the breech-block, compress the recoil-spring, and operate the arm. 80

3. In an automatic firearm a frame, a barrel rigidly mounted in said frame, a breech-block slidably mounted in the frame, a momentum-block slidably mounted in the frame and in operative contact with the breech-block, a recoil-spring, and means for stopping the breech-block after a short primary movement imparted by an explosion in the barrel and imparting energy to the momentum-block through the short primary movement of the breech-block to release the breech-block and retract it along the frame, compress the recoil-spring and operate the arm. 100

4. In an automatic firearm, a frame, a barrel fixed in said frame, a breech-block having an interrupted movement slidably mounted in said frame, a momentum-block mounted in contact with the breech-block and holding the breech-block in forward position when said parts are in closed position and receiving a recoil momentum from the breech-block upon the discharge of the arm, a spring in operative contact with the momentum-block, a locking-dog in operative contact with the breech-block and frame when said parts are in locked position and allowing a slight backward movement of the breech-block, said momentum-block being provided with means to operate the locking-dog into and out of locked position upon its backward and forward movements and to reciprocate the breech-block on the frame. 115

5. In a firearm, a frame, a breech-block slidably mounted in said frame, a locking-dog pivoted to said breech-block, and having at its forward end a cartridge-extracting hook, and means for reciprocating the breech-block and causing the hook to engage the cartridge and extract the same.
6. In an automatic firearm, a frame, a breech-block slidably mounted in said frame, a hammer having a cocking-notch pivotally mounted in said frame, two sears of unequal length pivotally mounted in said frame so as to engage separately the notch on the hammer, a trigger pivoted to said frame and having an extension formed thereon in the path of the shortest sear, and a member pivoted thereon and yieldingly held in the path of the longer sear, an inclined abutment on the frame to throw the movable member on the trigger out of engagement with the longer sear, and means for cocking the hammer and allowing the sears to consecutively engage the notch in the hammer upon the trigger being pulled.
7. In an automatic firearm, a frame, a barrel mounted in said frame, a breech-block mounted in said frame, a momentum-block mounted in said frame in operative contact with said breech-block, the breech-block having a short primary movement imparted by an explosion in the barrel and a longer secondary movement derived from the momentum-block, and means to transfer the energy of an explosion in the barrel through the short primary movement of the breech-block to the momentum-block to operate the arm.
8. In an automatic firearm, a frame, a barrel mounted in said frame, a breech-block mounted in the frame and having a short backward primary movement given it by an explosion in the barrel, means for stopping this primary movement, said breech-block also having a secondary longer movement, a momentum-block mounted in said frame and receiving sufficient energy from the short primary movement of the breech-block to unlock the breech-block, impart to it the longer secondary movement thus opening the breech of the arm and operating the other parts of the mechanism.
9. In an automatic firearm, a frame, a barrel mounted on the frame, a breech-block mounted in the frame, means for stopping the breech-block after it has been moved back a definite distance by an explosion, and a device co-operating with the breech-block and receiving movement therefrom to release the breech-block and carry it farther backward and operate the arm.
10. In an automatic firearm, a frame, a barrel mounted on the frame, a breech-block mounted in the frame and movable backward by successive steps, the movement of the breech-block through the first step being accomplished by the explosion, and means deriving energy from the breech-block during its first step for moving backward and for pulling the breech-block therewith through its next step.
11. In an automatic firearm, a frame, a barrel mounted on the frame, a breech-block mounted in the frame and movable through consecutive steps, means normally locked for stopping the breech-block at the end of its first step which is caused by the explosion, and a device deriving energy from the breech-block as it moves through the said first step for unlocking said means, thereby releasing said breech-block, and for moving the breech-block through its said second step and operating the arm.
- In testimony whereof I have hereunto set my hand, at Los Angeles, California, this 4th day of August, 1904.
- CHARLES FREEMAN.
